UNITED STATES PATENT OFFICE.

GEORGE H. ABEEL, OF ST. LOUIS, MISSOURI.

HAND LASTING-MACHINE.

SPECIFICATION forming part of Letters Patent No. 605,770, dated June 14, 1898.

Application filed January 11, 1897. Serial No. 618,865. (No model.)

To all whom it may concern:

Be it known that I, GEORGE H. ABEEL, of the city of St. Louis, State of Missouri, have invented certain new and useful Improvements in Hand Lasting-Machines, of which the following is a full, clear, and exact description, reference being had to the accompanying drawings, forming a part thereof.

My invention relates to hand lasting-machines; and it consists in the novel construction, combination, and arrangement of parts hereinafter shown, described, and claimed.

Figure 1 is a front elevation of my improved hand lasting-machine as it will appear to the operator when holding it in his right hand in position for use. Fig. 2 is a rear elevation of the machine, parts being broken away to economize space and to more clearly illustrate the same. Fig. 3 is a front

20 elevation, upon an enlarged scale, of the upper jaw of the machine, parts being removed and other parts being broken away to more clearly illustrate the same. Fig. 4 is a horizontal sectional view taken approximately on the line 4-4 of Fig. 3. Fig. 5 is a horizontal sectional view taken approximately on the line 5-5 of Fig. 3. Fig. 6 is a horizontal sectional view similar to Fig. 5 as the parts will appear when the hammer is elevated and about to drive a tack. Fig. 7 is a transverse sectional view taken approximately on the line 7-7 of Fig. 2 and looking in the direction indicated by the arrow. Fig. 8 is a side elevation of the shifter. Fig. 9 is a horizontal sectional view taken approximately on the line 9-9 of Fig. 8. Fig. 10 is a view in perspective, showing the double joint in the lever which operates the lower jaw of the machine. Fig. 11 is a plan view of the upper end of the tack-chute, parts being shown in section to more clearly illustrate the construction. Fig. 12 is a view in perspective of the tack-holder. Fig. 13 is a view in perspective of a spring. Fig. 14 is a view in perspective of the foot which supports the machine when in operation. Fig. 15 is a view in perspective of a connecting-rod of which I make use. Fig. 16 is a view in perspective of the bell-crank lever of which I make use. Fig. 17 is

40 a top plan view, upon an enlarged scale, of the tack-picker, parts being broken away to

economize space. Fig. 18 is a view in perspective of the entire picker shown in Fig. 17. Fig. 19 is a view in perspective of a pawl. Fig. 20 is a view in perspective of the part 55 engaged by the pawl shown in Fig. 19. Fig. 21 is a view in perspective of the sliding block which operates the pawl shown in Fig. 19. Fig. 22 is a view in perspective of the shipper-bar which operates the picker shown 60 in Fig. 18. Fig. 23 is a vertical central longitudinal section of the machine. Figs. 24, 25, 26, and 27 are views analogous to Fig. 4 and drawn for the purpose of illustrating the operation of the picker and the picker-shifter.

My improved hand lasting-machine consists of three principal parts—viz., the pincers, the tack-feeding mechanism, and the hammer.

The pincers consist of the upper jaw 25, having the handle 26 formed integral with its rear end, the lower jaw 27, pivotally mounted in operative position relative to said upper jaw, the lever 28, pivotally mounted in position to form a knuckle-joint with the rear end of said jaw 27, and the handle 29, connected to said lever 28. The plate 30 is placed against the front side of the handle 26 and at the point where said handle joins the upper jaw 25, and the pins 31 and 32 are inserted through said plate and through said handle. Upon the lower face and near the forward end of the jaw 25 are teeth 33, and upon the upper face and forward end of the jaw 27 are similar teeth 34, and the jaw 27 is placed in position against the plate 30, with the teeth 34 in opposition to the teeth 33, and the pin 35 is inserted through said plate and through the rear end of said jaw 27 in such a way that said jaw may turn upon said pin. In the rear end of the jaw 27 and upon the opposite side of the pin 35 from the teeth 34 is a recess 36, formed from the end surface of said jaw, the inner end of said recess being semicircular or rounded. The lever 28 has a circular portion 37 upon its forward end which operates in said recess 36, and a neck which connects said circular portion with the body of said lever 28, thus forming a knuckle-joint between the lever 28 and the jaw 27 when said jaw is placed in position against the plate 30 and loosely

mounted upon the pin 39. A plate 40 is placed in position against the rear faces of the handle 26, the rear end of the jaw 27, and the lever 28, and said pins 31, 32, 35, and 39 5 extend through said plate and hold it securely in position.

The foot 41 is formed of a metal strap bent into the desired shape and consists of the portion 42, which is substantially horizontal, the 10 portion 43, which extends upwardly from the rear end of the portion 42 and has the notch 44 in its upper end, thus forming the projections 45 and 46, and the portion 47, which is bent upwardly and backwardly from the front 15 end of the portion 42 to an angle of about twenty degrees and has the notch 48 formed in its upper end, thus forming the projections 49 and 50, which are bent upwardly and forwardly from the body of said portion 47. The 20 foot thus formed is placed in position below the jaw 27 and somewhat behind said jaw, and the projections 45 and 49 are driven tightly into slots formed in the lower edge of the plate 30, while the projections 46 and 50 25 are driven into corresponding slots formed in the lower edge of the plate 40, thus holding said foot securely in position relative to the machine.

The handle 29 is of irregular shape and is 30 connected to the rear end of the lever 28, as shown in Fig. 10. An ear 51 extends backwardly from the center of the rear end of the lever 28 and is approximately one-third as wide as the body of said lever, thus forming 35 the shoulders 52 and 53 at the junction of said ear with the body of said lever, and said shoulders are at approximately right angles to the top and bottom surfaces of said lever. The forward end of the handle 29 is bifurcated 40 to receive the ear 51, and a screw 54 is inserted from the rear side through the arm 55, then through the ear 51 and into the arm 56 to form a pivotal connection between the levers 29 and 28. The upper forward corners 45 of the arms 55 and 56 are rounded, as required to allow the handle 29 to bend upwardly from its normal position relative to the lever 28, while the lower forward corners of said arms 50 are square and fit against the shoulders 52 and 53, as required to prevent said handle 55 from bending downwardly from its normal position relative to the lever 28. The plates 30 and 40 are substantially the same size, the plate 40 being broken away in Fig. 2 to more 60 clearly illustrate the construction between the plates. The arm 57 extends forwardly from the arm 56 upon the front side of the plate 30 and on the opposite side of said plate from the lever 28 and to a point beyond the 65 circular portion 36 of said lever. Said arm 57 is substantially straight and in alignment with the arms 55 and 56, and from the front end of the arm 57 an arm 58 extends forwardly and upwardly and terminates in the rounded lower front surface 59. Near the center of the arm 57 is a screw-threaded aperture 60, and at the junction of the arm 57

with the arm 58 is a screw 61, screw-seated in said arms.

Extending upwardly from the rear end of the plate 40 is an arm 62, and extending forwardly from the upper side of said plate 40 is an arm 63. An arm 64 extends upwardly from the forward end of the plate 30 to a point nearly on a level with the upper end of the 75 arm 62. In the upper side of the jaw 25 and near its forward end is a dovetailed slot 65, extending transversely of said jaw, and a tubular block 66 has a dovetail upon its lower end which fits tightly within said slot 65, thus 80 forming a connection between said block and said jaw. The inner face 67 of the block 66 is substantially straight and joins the upper face of the jaw 25 at an angle of approximately forty-five degrees and at such an angle 85 that the handle 26 stands at approximately right angles to said block. A screw 68 is inserted through the forward end of the arm 63 and screw-seated in said block 66, thus forming an additional support and brace for said 90 block 66. Extending upwardly from the upper end of the block 66 is a cylindrical portion 69, and a bore 70 is formed through said cylindrical portion 69 and in a straight line through said block 66. The plunger 71 operates within the bore 70 and is of such size 95 as that it will fit closely within said bore and operate freely. The stem 72 extends upwardly from the plunger 71 to a position some distance above the upper end of the cylindrical portion 69, and the upper end of said stem is screw-threaded. In the inner side of the cylindrical portion 69 is formed a slot 73, which extends from the upper end of the block 66 nearly to the upper end of said cylindrical portion in a line radially relative to the center of the plunger 71 and parallel with the bore 70. The cap 74 is screw-seated upon the upper end of the cylindrical portion 69, and an aperture is formed through said cap, 100 which aperture serves as a bearing for the stem 72. The slot 73 extends upwardly partly through the cap 74. A packing-ring 75 is placed on top of the cap 74 around the stem 72, and a nut 76 is screw-seated upon said 105 stem above said packing-ring and is held securely in position by the jam-nut 77, which operates against the upper side of said nut 76. The stroke of the plunger 71 is regulated by manipulating the nuts 76 and 77, and the 110 packing-ring 75 acts as a buffer for the nut 76. In the lower end of the plunger 71 is formed a bore extending partly through said plunger, in which is seated the driving-head 115 or hammer 78. The block 79 is of such a size 120 as that it will readily slide in the slot 73, and said block is secured to the plunger 71 by means of the screw 80, and the inner end of said screw 80 engages in a recess in the upper 125 end of the hammer 78 and holds said hammer 130 securely and removably in position. Projecting from the inner and rear side of the block 79 is a pair of apertured ears 81, between which is pivotally mounted the connecting-rod 82

by means of a pin passing through said ears and through the lower end of said connecting-rod.

A lever 84 (shown in detail in Fig. 20) is pivotally connected to the upper end of the arm 64 by means of the bolt 85. A circular lug 86 projects from the front side of the upper end of the arm 64, and the bolt 85 is screw-seated or riveted through said lug, as required to form a substantial and rigid support for said bolt, and the nut 87 is screw-seated upon the rear end of said bolt, as required to hold said lever 84 removably in position. The upper end of the connecting-rod 82 is pivotally connected to the forward end of the lever 84 by means of a screw 87^a, passing through said forward end and screw-seated in the upper end of said connecting-rod. The rear end of the lever 84 terminates in the lug 88, the upper line of which is slightly concaved or curved downwardly relative to a straight line from end to end through said lever. Projecting downwardly from the rear portion of said lever 84 is a segmental or semicircular portion 89, arranged substantially concentric to the bolt 85, and ratchet-teeth 90 are formed upon the forward and lower edge of said segmental portion, said teeth pointing downwardly and backwardly. The pawl 91 (shown in Fig. 19) is pivotally mounted against the rear side of the arm 64 by means of the pin 92 and in position to have its upper end engage the teeth 90.

A spring 93 has its rear end attached to the rear face of the arm 64, and said spring extends upwardly and is coiled around the pin 92 and then extends downwardly, and its forward end is attached to the lower end of the pawl 91, as required to have the tension of said spring exerted to force the lower end of said bolt backwardly, and thus hold the upper end of said bolt normally in engagement with said teeth 90. The lever 94 (shown in detail in Fig. 16) is in the form of a bell-crank, and upon the upper end and front side of said lever is formed a lug 95, through which lug a bearing is formed for the pin 96, and said pin is riveted in position in said lug, and the roller 97 is rotatably mounted upon the end of said pin and against the rear side of said lever. In the lower forward end of the lever 94 is a segmental slot 98. A bolt 99 is fixed in position to project forwardly from the face of the arm 64 at a point approximately in the center of said arm, and the lever 94 is placed in position with the bolt 99 operating through the slot 98. A connecting-rod 100 (shown in Fig. 15) is placed in position to connect the arm 57 with the lever 94. The screw 101 is placed through the lower end of the connecting-rod 100 and is screw-seated in the aperture 60 in said arm 57. A circular lug 102 projects backwardly from the upper end of said connecting-rod 100 and is inserted in the aperture 103, which aperture is formed in the angle of the lever 94 and at approximately

right angles relative to the pin 95 and the slot 98. The lower end 104 of the connecting-rod 100 is offset relative to the body of said connecting-rod, as required to bring the rear face of said body of said connecting-rod against the front face of the plate 30 and to bring said lower end 104 against the front face of the arm 57.

The sliding block 105 (shown in detail in Fig. 21) is placed in position against the upper face of the handle 26, and the portion 106 of said block extends forwardly behind the arm 64 and has a recess 107 in its forward end, in which the lower end of the pawl 91 operates. The portion 108 of said block extends transversely behind the arm 64 and the portion 109 extends forwardly from the end of the portion 108 and outside of the arm 64 and engages against the rear side of the connecting-rod 100, and the portion 110 of said block extends forwardly from the portion 109 and engages the outer surface of said connecting-rod 100. The spring 111 has its rear end 112 fixed in the handle 26, and said spring extends upwardly and forms the coils 113, then downwardly to a position against the upper face of the arm 26, and the front end 114 of said spring engages the rear end of the block 105, as required to have its tension exerted to normally hold said block forwardly. The roller 97 normally engages above the portion 88 of the lever 84. When the operator brings the handles 26 and 29 together, the connecting-rod 100 will pull backwardly and downwardly upon the lever 94, thus depressing the portion 88 of the lever 84 and elevating the front end of said lever, and thereby elevating the plunger 71 and the hammer 78. As the front end of the lever 84 is elevated gradually the pawl 91 will engage the teeth 90 and hold said lever in its elevated position. When the lever 94 tips backwardly, the upper end of the connecting-rod 100 will also tip backwardly, and as said connecting-rod 100 is drawn downwardly the sliding block 105 will be forced backwardly, and at the time the roller 97 leaves the portion 88 of the lever 84 the pawl 91 will be out of engagement with the teeth 90, thus leaving the forward end of the lever 84 free to be again depressed.

The tack-chute is constructed, as shown, in cross-section in Fig. 7 and consists of the upper guide-bar 115 and the lower guide-bars 116 and 117. The lower guide-bars 116 and 117 are arranged in parallel position in the same horizontal plane and a sufficient distance apart to allow the body portion of the tack to pass freely between them. The head of the tack rests upon the upper edges of said bars 116 and 117, and the guide-bar 115 is mounted directly above the head of the tack, the lower edge of said bar 115 being parallel with the upper edges of the bars 116 and 117 and said bar 115 occupying a vertical plane directly above the space between said bars 116 and 117. The rear upper end of the bar 115 is attached to the upper end of the arm

62 by means of the screw 118, which screw is inserted from the rear side of said arm and is screw-seated in the lug 119, projecting upwardly from said bar 115. The lug 119 is of such a thickness that the bar 115 does not come directly against arm 62 and is offset to bring it in the desired position. The rear upper ends of the bars 116 and 117 are attached to the arm 62 by means of the rivet or screw 120, which rivet or screw passes through said arm 62 and then through the arms 121, which project downwardly from said bars 116 and 117, and said arms 121 are so formed as to bring said bars 116 and 117 in the desired position relative to the bar 115 and the desired distance apart relative to each other. The bars 115, 116, and 117 extend forwardly and downwardly at an angle of approximately forty-five degrees and lead the tacks to a point in the block 66 below the hammer 78 when said hammer is in its elevated position. The lower forward end of the bar 115 extends to the face of the block 66, and the lug or arm 122 extends into said block, as required to form a support for said forward end. The front side of the block 66 is cut away at its lower portion, as shown in Figs. 4, 5, and 6, and the front lower end of the bar 116 extends into said cut-away portion and is secured in position by means of the screw 123, (shown in Fig. 3,) which screw passes through said bar 116 and is screw-seated in said block 66. The forward end of the bar 117 extends into the cut-away portion in said block 66, and a lug 124 extends into a recess in said block, as required to hold said bar in position. A strengthening-strip 125 is formed upon the upper edge of the bar 115 and extends around the bolt 87, as shown in Fig. 2. A leaf-spring 126 is attached at its forward end to the front face of the bar 117 and extends backwardly to a position beyond the upper end of said bar, and a pin 127 is fixed to said spring near its free end, and said pin operates horizontally through openings 128 in said bars 116 and 117. A pin 129 is fixed to the free end of the spring 126 and extends horizontally across and near to the upper end of said bars 116 and 117. In feeding the tacks into the chute the lug 129 is operated to press the free end of the spring 126 away from the bar 117, and thus withdraw the pin 127 and allow the passage of the tacks down the chute. After the chute has been filled with tacks the lug 129 is released, allowing the pin 127 to return to its normal position, and thus preventing the tacks from passing backwardly out of said chute. The pin 127 is fixed through the upper end of the lug 130, which extends upwardly from the spring 126, the object being to get the pin 127 as near to the upper edges of the bars 116 and 117 as possible.

A rectangular aperture 131 is formed through the lower end of the bar 117, and an aperture 132 is formed through the bar 116 diagonally, said apertures 131 and 132 being substantially opposite each other. A leaf-

spring 133 is secured to the rear side of the bar 116 by means of the rivets 134, and the free end of said spring extends through the aperture 132 to a point near the throat 135, which throat is a continuation of the bore 70 through the ends of the bars 116 and 117 and is formed by concaving the adjacent faces of said bars. The aperture 131 intersects the throat 135.

The leaf-spring 136 (shown in Fig. 13) has its lower end 137 bent outwardly at right angles to its body and secured to the surface 138 by means of a rivet or screw passing through the aperture 139 and into the bar 117. The surface 138 forms the lower wall of the aperture 131. The body portion of the spring 136 is substantially vertical, and from the upper end of said body portion a curved spring-arm 140 extends to the free end of the spring 133, the free ends of said springs 133 and 140 meeting half-way between the adjacent faces of the bars 116 and 117 and near the throat 135, as shown in Fig. 6. As the tacks pass down the chute they are held in check by the springs 133 and 140 until forced between said springs by the manipulation of the machine.

In the front face of the upper jaw 25 is formed a slot 141, which slot is at right angles relative to the cylindrical portion 69 of the block 66, and the picker-bar 142 (shown in detail in Fig. 18) is slidingly mounted in said slot, the straight face 143 of said bar engaging the bottom or inner surface of the slot and the opposite face of said bar projecting outwardly from said jaw. The portion 144 of said bar slides behind the plate 30, as indicated in dotted lines in Fig. 1.

The picker proper, 145, is attached to the front end of the picker-bar and operates in the opening 131. The shipper-bar 146 (shown in detail in Fig. 22) has a screw-threaded pin 147 projecting backwardly from near its upper end, which pin is inserted through the lever 84 at a point approximately half-way between the screw 87^a and the bolt 85, and a nut 148 is screw-seated upon the rear end of said pin and against the rear surface of said lever 84 as required to form a pivotal connection between said lever 84 and the shipper-bar 146. The lower end 149 of the shipper-bar 146 is wedge-shaped, said wedge being formed by bifurcating said lower end and bending one of the parts backwardly and the other one forwardly. The shipper-bar 146 operates close to the front face of the jaw 25 and in contact with the front edge of the plate 30, and a recess 150 is formed in the lower front corner of said plate to receive the arm 151 of said shipper-bar when said bar is in its lowest position. The bar 146 is vertically reciprocated by the operation of the lever 84, and the arm 152 of said bar 130 engages the shoulder 153 upon the picker-bar 142, and when the bar 146 is elevated the arm 151, engaging the edge of the plate 30, will be forced forwardly, and the arm

152, engaging the shoulder 153, will force the picker-bar 142 forwardly. A perforated ear 154 is formed by bending the upper end of the bar 146 forwardly. A screw-eye 155 is inserted upwardly through the aperture in said ear and is held adjustably in position by the nut 156. A retractile coil-spring 157 is connected to the eye 155, and the lower end of said spring engages the screw 61 in the arm 57. A retractile coil-spring 158 engages the pin 99, which projects from the arm 64 and upon which the lever 94 operates, and the upper end of said spring engages the pin 159, which pin is rigidly fixed in the upper part of the lever 94, said spring operating to swing said lever forwardly and upwardly. A spring 160 is secured to the shipper-bar 146 and extends forwardly, forming the coil 161, and then downwardly, and its lower end 162 operates through the aperture 163 in the picker-bar 142. The spring 160 is attached to the bar 146 by means of the plate 164, as shown in Fig. 22. The end 162 of the spring 160 is reciprocated through the aperture 163 by the reciprocatory motion of the bar 146, and the tension of said spring operates to return the picker-bar 142 to its normal position after said picker-bar has been forced forward by the operation of said bar 146. Projecting outwardly from the center of the picker-bar 142 is an arm or lug 165, which engages the end of the arm 58. The upper corner 166 of the lug 165 is beveled. The picker 145 operates below the surface which forms the upper wall of the aperture 131, and said picker 145 is carried upon the inner end of the arm 167 and has the concaved front face 168, which face is vertical or parallel with the line of travel of the hammer. The upper end of the picker 145 is substantially on a level with the upper face of the picker-bar 142, while its lower end 169 extends some distance below said bar. In forcing a tack forward the picker 145 operates against the inner surface of the bar 116, and said picker forces the tack between the points of the springs 133 and 140, and said picker also passes between said points. The arm 167 extends through the opening 131 immediately above the spring 140. The lugs 170 and 171 are formed, respectively, upon the lower and upper faces and near the forward end of the picker-bar 142 and extend diagonally across said faces, the inner ends of said lugs being nearer the end of the bar than the outer ends.

The picker-shifter 172 (shown in Figs. 8 and 9) is seated in a rectangular recess in the block 66 in position directly above the opening 131 and is mounted upon the pivot 173, which extends through the upper end of said shifter and into said block 66. The picker-shifter 172 consists of the perforated ear 174, through which the pivot 173 operates, and the diagonal lugs 175 and 176, which lugs are connected by the circular or segmental bar 177, said bar also being attached to or formed integral with the ear 172. The lugs 175 and

176 are arranged upon diagonal lines corresponding to the lugs 170 and 171 and a sufficient distance apart to allow the arm 167 to pass between them. Between the lugs 175 and 176 and the bar 177 is a space 178, through which the end of the picker-bar 142 operates. The inner ends of the lugs 175 and 176 are normally held in a position in a line with the front surface of the bar 117 and in position to be engaged by the lugs 170 and 171. The spring 179 is held in position against the block 66 by means of the screw 180, and the free end of said spring engages against the outer edge and lower end of the ear 172 as required to hold the shifter in its normal position. When the picker-bar 142 is forced forwardly, the lugs 170 and 171 engage the inner faces of the lugs 175 and 176 and press them outwardly against the tension of the spring 179. When the picker returns to its normal position, said lugs 170 and 171 engage the outer surface of said lugs 175 and 176 and press the forward end of the picker-bar 142 outwardly, thus carrying the picker 145 backwardly upon the outside of the spring 140.

The tack-holder 181, which is shown in detail in Fig. 12, consists of the two mating parts 182 and 183, which parts are substantially alike, with the exception that one is right-handed and the other is left-handed. The upper ends 184 of the parts 182 and 183 are inserted in an aperture in the block 66 and are held in position by being engaged by the inner end of the screw 180. The portions 185 of said parts extend downwardly outside of the block 66 to a point below the lower end of said block. The blocks 186 are attached to the lower ends of said portions 185 in horizontal alinement with each other and side by side, and the meeting faces of said blocks are concaved, as required to form a vertical opening 187, which opening is substantially circular in cross-section and is larger in diameter at its upper end than at its lower end, and said opening is in vertical alinement with the throat 135 and with the bore 70. The portions 185 act as springs to hold the blocks 186 yielding together.

Assuming that the machine has been loaded with tacks and the parts are in position for operation, the operator grasps the handles 26 and 29 in his right hand, places the edge of the leather between the jaws 25 and 27, and places the foot 41 upon the last. It is necessary that the jaws grip the leather before the various other parts of the device operate to drive the tack. When the nut 76 is resting upon the buffer 75, the lever 84 is in an approximately horizontal position, or a position at right angles to the travel of the plunger 71. The upper end of the spring 157, being connected to the lever 84, is rigidly held from being drawn downwardly; and with the first movement or gripping of the handles 26 and 29 together the handle 29 moves toward the handle 26, fulcruming upon the pivot 39, the reason for this being that the spring 157,

which may be termed the "weight," is pulling upwardly on the end of the arm 57, and as said arm 57 is fulcrumed to the rear end of the lever 28 said rear end of said lever is likewise pulled upwardly. The shoulders at the forward ends of the arms 55 and 56 abut against the shoulders formed at the rear end of the ear 51, and said shoulders are so constructed as to make a knife-blade joint between the lever 28 and the handle 29, which joint allows said handle to break in one direction only and that direction being upwardly. The lever 28 fulcruming upon the pivot 39, said handle 29 will by reason of its being connected to said lever 28 fulcrum upon said pivot 39, and as said handle is moved upwardly toward the handle 26 the forward end of the lever 28 will operate in the socket formed in the rear end of the jaw 27 and the forward toothed end of said jaw will be thrown upwardly to grip the leather against the teeth 33 of the jaw 25. When the leather is gripped between said jaws and the jaw 27 can move no farther, the fulcrum-point of the handle 29 will be transferred from the pivot 39 to the pivot 54, the lever 28 having ceased to move with the stopping of the jaw 27. The tension or resistance of the spring 157 is during this movement constantly increasing, for the reason that the end of the arm 57, to which said spring is attached, is moving downwardly and expanding said spring. This operation also pulls downwardly upon the connecting-rod 100, causing the roller 97 to engage the projection 88 upon the rear end of the lever 84, and as said rear end of the lever is depressed the forward end of said lever is elevated, and consequently the hammer is elevated. When the hammer has reached its uppermost position, the roller 97 will slip from the projection 88 and allow the hammer to rebound to its normal position by the tension of the spring 157, which spring is pulling downwardly. The elevation of the forward end of the lever 84, as described, will cause the shipper-bar 146 to slide upwardly and force the picker-bar 142 forwardly, thus forcing the tack which is in front of the picker 145 into the throat 135. The end 59 of the arm 58 will engage against the rear side of the lug 165 and will hold the picker-bar 142 in its forward position, which is the position shown in Fig. 6, until the hammer descends and drives the tack. While the picker 145 is in the position shown in Fig. 6 it closes the open side of the throat 135 and prevents the tack from turning in said throat. When the tack passes into the throat 135, it will drop downwardly into the tack-holder 181, and the conical shape of the opening through said tack-holder will act as a means of centering said tack relative to the hammer and will hold said tack in position to be driven. When the hammer descends, the head of the tack and the face of the hammer will spread the blocks 186 between which the tack is held and allow said tack to pass downwardly through the leather and

into the last. When the grip upon the handles 26 and 29 is relaxed, the jaws will again open, the roller 87 will return to its position above the projection 88, the picker-bar will return to its normal position, the forward tack will pass to its normal position between the free ends of the springs 133 and 140, the picker in returning to its normal position will pass outside of the spring 140, and thus the point 168 will be brought behind the forward tack, which is between the points of the springs 133 and 140 and is in position when the machine is again operated to press said tack forwardly into position to be driven. When the shipper-bar 146 is elevated, the end 162 of the spring 160 reciprocates through the opening 163 in the picker-bar 142, but the tension of said spring is exerted against said picker-bar at all times. When the handles 26 and 29 are pressed together only a part of their limit of motion, the jaws 25 and 27 are brought together and the hammer is partially elevated and the pawl 91 holds said hammer in said elevated position. If the grip upon the handles be now relaxed, the jaws will open without driving the tack, although the tack may be in position in the tack-holder to be driven. The first part of the motion of the handle 29 toward the handle 26 will close the jaws, but it is the latter part of said motion which releases the hammer. Should the operator fail to apply the final grip to the handles, which will elevate the hammer to its highest position and release it and allow it to rebound, the tack will remain in the tack-holder until the next operation. After the hammer has been released by the slipping of the roller 97 from the projection 88 should the operator fail to sufficiently relax his grip to allow the handles to spread apart far enough to allow said roller to return to its position above said projection 88 the picker-bar 142 will not be operated because the shipper-bar 146 will not be operated, and then the forward end 59 of the arm 58 will strike the beveled corner 166 of the lug 165 upon said picker-bar and will slip or glance outwardly over said lug and the picker-bar will not be operated to feed a tack. This is an important feature, because if the picker-bar was operated by every motion of the handles, whether or not the hammer was elevated, the tacks would become clogged in the throat 135, but by the construction described the tacks will not be fed to the throat 135 faster than they are driven by the operation of the hammer.

While my improved hand lasting-machine contains all the mechanism required for the purposes described, it is not too heavy to be operated easily and its operation will prove very efficient and satisfactory.

I claim—

1. In a hand lasting-machine, an upper jaw, a handle rigidly connected to said upper jaw, a lower jaw pivotally mounted in position to engage said upper jaw, a lever pivotally

5 mounted in position to operate said lower jaw, a handle hinged to the end of said lever opposite the end which engages said lower jaw, an arm projecting forwardly from said last-mentioned handle, and a yielding connection between said arm and the first-mentioned handle, whereby said lower jaw is yieldingly operated by the opposition of said last-mentioned handle, substantially as specified.

10 2. In a hand lasting-machine, a suitable frame, an upper jaw rigidly connected to said frame, a handle rigidly connected to said frame, a lower jaw pivotally mounted in position to engage said upper jaw, a lower handle pivotally connected to said frame, and a yielding connection between said lower handle and said lower jaw, substantially as specified.

15 3. In a hand lasting-machine, an upper jaw having a rigid handle, a lower jaw pivotally mounted in position to engage said upper jaw, a second handle mounted to yieldingly operate said lower jaw, a tubular block rigidly connected to said upper jaw, a plunger operating in said block, a hammer carried by said plunger, connections between said plunger and said second handle whereby the hammer is elevated and caused to rebound by the operation of said second handle, and a tack-chute leading to a point within said tubular block and below said hammer when in its elevated position, substantially as specified.

20 4. In a hand lasting-machine, a suitable frame, an upper jaw rigidly connected to said frame, a lower jaw pivotally mounted in position to engage said upper jaw, a lever pivotally mounted in said frame and operating said lower jaw, a lower handle hinged to said lever, a yielding connection between said lower handle and said frame whereby the lower jaw is yieldingly operated and a foot extending from said frame below said lower jaw, substantially as specified.

25 5. In a hand lasting-machine, a suitable frame, an upper jaw rigidly connected to said frame, a tubular block mounted in position above the point of said upper jaw, a hammer operating in said tubular block, a tack-chute leading into said tubular block below said hammer, a lower jaw pivotally mounted in position to engage said upper jaw, a lever pivotally mounted in said frame and operating said lower jaw, a lower handle hinged to said lever, a second lever pivotally mounted above 30 said rigid jaw, a connection between the front end of said second lever and said hammer, an arm projecting forwardly from said lower handle, a yielding connection between the forward end of said second lever and said arm, and a trigger connection between the rear end of said second lever and said arm, substantially as specified.

35 6. In a hand lasting-machine, a suitable frame, an upper jaw rigidly connected to said frame, a tubular block mounted in position above the point of said upper jaw, a hammer operating in said tubular block, a tack-chute

leading into said tubular block below said hammer, a lower jaw pivotally mounted in position to engage said upper jaw, a lever pivotally mounted in said frame and operating said lower jaw, a lower handle hinged to said lever, a second lever pivotally mounted above said rigid jaw, a connection between the front end of said second lever and said hammer, an arm projecting forwardly from said lower handle, a yielding connection between the forward end of said second lever and said arm, a trigger connection between the rear end of said second lever and said arm, a picker mounted to slide horizontally and feed tacks one at a time from said tack-chute into said block, a connection between the forward end of said second lever and said picker whereby the picker is pressed forwardly and a projection carried by said picker to engage the forward end of said arm and hold the picker in position to close the throat in said tubular block while the tack is being driven, substantially as specified.

40 7. In a hand lasting-machine, a suitable frame, the upper jaw 25, the handle 26 formed integral with said upper jaw, the lower jaw 27 pivotally mounted in an operative position relative to said upper jaw, the lever 28 pivotally mounted in position to form a knuckle-joint with the rear end of the jaw 27, the handle 29 hinged to the rear end of said lever 28, the foot 41 mounted in position below the lower jaw, the arm 57 projecting forwardly from the handle 29 and a yielding connection between the forward end of said arm and the frame of the machine, substantially as specified.

45 8. In a hand lasting-machine, the upper jaw 25, having the slot 141 formed in its front face in a substantially horizontal line, the tubular block 66 rigidly connected to said jaw, a tack-chute leading into said tubular block, the picker-bar 142 slidably mounted in said slot 141, the picker 145 attached to the front end of the picker-bar, the shipper-bar 146 mounted for vertical reciprocation and the lug 165 projecting outwardly from the picker-bar and engaging the front face of the shipper-bar 115 and in position to engage the front end of the arm 57, substantially as specified.

50 9. In a hand lasting-machine, the picker-bar 142 slidably mounted in a horizontal position, the shipper-bar 146 mounted for vertical reciprocation, the lug 165 projecting from the picker-bar and engaging the front face of the shipper-bar and the spring 160 connecting said picker-bar with said shipper-bar, substantially as specified.

55 10. In a hand lasting-machine, the picker-bar 142 slidably mounted in a horizontal position, means for operating said bar, the picker 145 attached to the front end and inner face of said bar, the lugs 170 and 171 formed upon the upper and lower faces of the forward end of said bar, the picker-shifter 172 yieldingly mounted, the diagonal lugs 175 and 176 carried by said picker-shifter in position

to be engaged by the lugs 170 and 171 carried by the picker-bar, substantially as specified.

11. In a hand lasting-machine, the lever 84 pivotally mounted, the segmental portion 89 arranged concentric to the pivot of said lever and projecting downwardly, the ratchet-teeth 90 formed upon the lower edge of said segment, said teeth pointing downwardly and backwardly, the pawl 91 pivotally mounted

in position to engage said teeth, means for operating said lever, and means of operating said pawl, substantially as specified.

In testimony whereof I affix my signature in presence of two witnesses.

GEORGE H. ABEEL.
